UNITED STATES PATENT OFFICE.

PETER KAUFMANN, OF PORTLAND, OREGON.

SPIRIT-LEVEL.

SPECIFICATION forming part of Letters Patent No. 794,865, dated July 18, 1905.

Application filed April 8, 1904. Serial No. 202,216.

To all whom it may concern:

Be it known that I, PETER KAUFMANN, a citizen of the United States, residing at Portland, in the county of Multnomah and State of Oregon, have invented a new and useful Spirit-Level, of which the following is a specification.

This invention is an improved construction of spirit-level, the object being to provide a cheap, simple, and efficient device in which the spirit-tube can be quickly and easily adjusted for the purpose of rendering the level absolutely accurate.

Spirit-levels as usually constructed have no means for readjusting the spirit-tube, and it is a well-known fact that levels frequently become inaccurate owing to the expansion or contraction of the metal parts or the warping of the wooden stock or from a sudden jar or fall. Furthermore, these ordinary spirit-levels have no convenient means for readjustment, and the usefulness of the device as an accurate tool is consequently impaired.

The object of my invention is therefore to avoid these objections; and with this object in view my invention consists, essentially, in the employment of a spirit-tube holder arranged within an opening in the stock, together with adjustable means for securing said tube-holder within said opening.

The invention consists also in certain details of construction hereinafter fully described, and pointed out in the claim.

In the drawings forming a part of this specification, Figure 1 is a perspective view of a spirit-level constructed in accordance with my invention. Fig. 2 is a transverse vertical section on the line 2 2 of Fig. 3. Fig. 3 is a vertical longitudinal sectional view on the line 3 3 of Fig. 2, and Fig. 4 is a horizontal sectional view on the line 4 4 of Fig. 3.

In constructing a spirit-level in accordance with my invention I employ a stock A, preferably of wood and having an essentially rectangular opening A' at the center of the same, and fitting in said opening is an essentially rectangular-shaped metal frame B, which is securely held in place by means of screws C, passing through the top and bottom of the

stock into the frame, as most clearly shown in Fig. 3. The side members of the frame B are preferably provided with openings B', in which rest the ends of the cylindrical spirit-tube holder D, said tube-holder being opened at both ends and has the spirit-tube E arranged therein, the top and bottom sides of the said tube-holder being cut away, as shown at D', in order to expose the bubble E' in the spirit-tube E. This tube is securely held at the proper point in the holder by means of any suitable adhesive.

Passing vertically through the tube-holder D and beyond the ends of the spirit-tube are the threaded rods F, the ends of which are fastened in the top and bottom sides of the frames, and jam-nuts G are arranged upon the said threaded rods and adapted to bear against the frame and securely hold the said rods from turning. Nuts H are arranged upon the rods F above and below the holder D and securely hold said holder in its proper position, and it is obvious that by adjusting these nuts the spirit-tube can be accurately adjusted, so that the bubble will appear exactly at the center when the stock is perfectly level.

By having the tube-holder cut away upon the top and bottom sides the level is reversible—that is, it can be used either side up. After the spirit-tube has been once accurately adjusted it is obvious that it can be quickly readjusted should it become deranged from any cause whatever.

Having thus fully described my invention, what I claim as new, and desire to secure by Patent, is—

A spirit-level comprising a stock having an opening therein, a frame arranged in said opening, a cylindrical tube-holder arranged horizontally within the frame, a spirit-tube arranged in the holder, the threaded rods fixed in the frame, and passing through the tube-holder, and the nuts upon the rods above and below the tube-holder for the purpose set forth.

PETER KAUFMANN.
